UNITED STATES PATENT OFFICE.

JOHN L. ATWATER, OF WESTERN SPRINGS, ILLINOIS, ASSIGNOR TO THE
VIVE CAMERA COMPANY, OF CHICAGO, ILLINOIS.

MAGAZINE-CAMERA.

SPECIFICATION forming part of Letters Patent No. 595,591, dated December 14, 1897.

Application filed February 27, 1897. Serial No. 625,260. (No model.)

To all whom it may concern:

Be it known that I, JOHN L. ATWATER, a citizen of the United States, residing in Western Springs, in the county of Cook and State 55
of Illinois, have invented a new and useful Improvement in Photographic Hand-Cameras, of which the following is a specification.

This invention relates to that class of hand-cameras in which a magazine of plate-holders is provided, the plate-holders being compressed in a body against a shoulder and so arranged that through a flexible changing-cuff the foremost plate may be shifted to the rear and an unexposed plate brought into position for exposure, the changing-cuff being connected to the camera-box and its lid in such manner as to afford ready access to the plate-holders and permit of manipulation of the same in a light-tight chamber; and the 15
present invention consists in adding to such a camera-box a simple, cheap, and effective device for making the plate-holders as a whole bodily adjustable to and from the lens for changing the focus. This is done by 20
means of mounting the plate-holders in a thin sheet-metal shell of peculiar construction contained in the camera-box and movable therein by means of an adjusting device, as will be more fully hereinafter described.

30 In the accompanying drawings, which form a part of this specification, and in which similar letters of reference indicate like parts in the several views, Figure 1 represents a perspective view of the exterior of a camera-box. Fig. 2 is a longitudinal central vertical section of the same, and Fig. 3 is a perspective view of the movable sheet-metal casing.

In said drawings, A is the light-tight rigid camera-box, provided with the cover A' and 40
flexible changing-cuff A², the whole constituting a rectangular light-tight box.

B is a plate of sheet metal cut and stamped up into the form shown at Fig. 3—that is to say, having a bottom piece and two upright 45
sides B' B². At B² B² the ends of the uprights are folded or turned inward to form shoulders, and projections B³ B³ are formed in the said uprights adjacent to said shoulders B². The space between the shoulders 50
B² and projections B³ constitutes a groove, into which is slipped a wooden end or back-

ing plate B⁴. (See Fig. 2.) This backing-plate B⁴ carries a spring B⁵. At a suitable distance in front sufficient to accommodate the required number of plate-holders other 55
projections B⁶ are formed in the uprights B' to constitute a shoulder against which the plate-holders are pressed by said spring and forming the focal plane. On the bottom of the shell is a rack or racks B⁷, and in the vertical sides opposite thereto are cut slots B⁸ B⁸ horizontally. A pinion or pinions B⁹, mounted on a shaft B¹⁰, engages these racks, the ends of the shaft having bearings in the camera-box, and one end being fitted with a key 60
or index-finger B¹¹, and the camera-box adjacent thereto being provided with an index-arc B¹², which may be marked with an index of focal distances.

The operation is as follows: The shell, with 70
its wooden backing-plate and spring, is placed loosely in the camera-box, so that it shall be free to move backward and forward. The shaft, with its gear and turning key or finger, is then inserted and the camera is ready for 75
use. When the magazine is filled with plate-holders and the movable shell is in the position shown at Fig. 2, the foremost plate of the series is in the plane of infinite focus of the lens. To adjust the foremost plate to a 80
different focus, the index-finger is turned, rotating the cog-pinion, which moves the shell back from the lens and carries the plate to the required position indicated by index-arc.

The construction is such that the solidity, 85
compactness, and light-tight character, as well as the means of attachment of the flexible changing-bag and its co-operative lid, are not in any manner interfered with by the addition of the movable shell, while at the 90
same time this movable shell is of such form and nature that it may be very cheaply made by simply stamping it out of sheet metal and bending it up to form. This gives as a whole 95
a camera of very cheap and simple construction, capable of taking a large picture relatively to the size of the camera-box, one in which the plates may be easily changed, and one in which the focus may be set as required arbitrarily from the exterior. 100

I claim—

1. The combination with the rectangular

light-tight camera-box of the character indicated, of the three-sided metal shell formed with a groove for a rigid backing-plate and containing said backing-plate provided with 5 a spring, and formed with a shoulder at each side for the plates to abut against, and means for moving said shell to and from the lens from the exterior, substantially as specified.

2. The combination with the rectangular 10 light-tight camera-box of the character indicated, of the three-sided metal shell formed with a groove for a rigid backing-plate and containing said backing-plate provided with

a spring, and formed with a shoulder at each side for the plates to abut against, and means 15 for moving said shell to and from the lens from the exterior, said means consisting of a rack on the bottom of the shell, a shaft extending through the camera-box and the shell, and an exterior key or index-finger and an 20 index-plate, substantially as specified.

JOHN L. ATWATER.
